CHILD'S GARMENT

Melvin G. Sladek and Ralph M. Proby,
Chicago, Ill.

Application April 22, 1947, Serial No. 743,080

4 Claims. (Cl. 2-227)

1

The invention relates generally to a child's garment and more particularly to a trousers-like garment for children from four to eighteen months of age.

Children from four to eighteen months of age spend much time playing in their cribs or on the floor or in play pens on the floor where the temperature is low, drafts are common and where there is a great deal of dirt. At this age children have a great propensity for removing their booties and their socks with the result that much of the time the child's feet and legs are bare and uncovered.

It is an object of this invention, therefore, to provide a new and improved trousers-like garment having feet which may be worn by the child to take the place of booties or shoes, stockings and a romper or other garment normally worn by the child.

Another object is to provide a new and improved garment of the character described which is constructed to be completely free of buttons, zippers, tie strings or other fastening means so as to facilitate the putting on or the taking off of the garment and eliminate any means that might bind the child or come open during play.

Another object is to provide a garment of the character described having a unique cut or style and which is quickly and efficiently manufactured.

Still another object is to provide a trousers-like garment with feet in which each foot portion of the garment is composed in the main of but two pieces and in which the sole portion is smooth and free of seams so as not to interfere with walking while the garment is worn.

Other objects and advantages will become apparent from the following detailed description taken in connection with the accompanying drawings, in which:

Fig. 1 is a perspective view of a garment embodying the features of this invention.

Fig. 2 is a view showing in plan the cut of the piece of goods forming the front half of the trouser leg.

Fig. 3 is a view showing in plan the cut of the piece of goods forming the rear half of the trouser leg.

Fig. 4 is a view showing in plan the piece forming the instep of the boot portion.

Fig. 5 is an enlarged sectional view taken approximately along the line 5-5 of Fig. 4 and showing a detail of construction.

Fig. 6 is a plan view showing the sole-forming piece of the boot.

2

Fig. 7 is a fragmentary and enlarged sectional view taken approximately along the line 7-7 of Fig. 6 illustrating the detail of construction of the sole-forming portion.

Fig. 8 is a fragmentary, very substantially enlarged sectional view showing the manner in which the instep portion and the sole-forming portion are sewn together.

While the invention is susceptible of various modifications and alternative constructions, it is shown in the drawing and will hereinafter be described in a preferred embodiment. It is not intended, however, that the invention is to be limited thereby to the specific construction disclosed. On the contrary it is intended to cover all modifications and alternative constructions falling within the spirit and scope of the invention as defined in the appended claims.

The garment forming the subject matter of this invention takes on the general form of a pair of trousers or trunks with feet and is thus composed in the main of a pair of legs 10 each terminating in a foot or boot 11 integral therewith. Each leg is composed of but two parts 12 and 13 having a generally similar cut save for certain differences that will presently be made known. Herein reference character 12 indicates the front part and reference character 13 the back part of a leg. Each of the parts has a top edge 14 substantially straight, and an outer edge 15 somewhat convex to give required fullness and a pleasing shape to the finished garment. The inner edge of each part has a compound curvature or cut with slightly less than half of the upper portion of each part shaped to take on the form of a half of a U. This portion of the inner edge is herein designated by the reference character 16. The lower slightly more than half of the inner edge of each part is slightly concave and intersects the upper edge portion 15 to form a point 17. The lower half of the inner edge is designated by the reference character 18 and it will be appreciated that the point 17 represents the lowest point in the crotch of the garment.

Except for increased width of the part 13, particularly at the point 17, so as to give the necessary fullness to the seat of the garment, the parts 12 and 13 as so far described are substantially the same. It is to be noted, however, and can readily be seen in Figs. 2 and 3, that the part 13 extends upwardly from a transverse line drawn through the point 17 a greater distance than does the part 12, and similarly part 13 extends downwardly a greater distance from that

line than does the part 12. Part 13 has a bottom edge 19 which is very slightly concave, while part 12 has a bottom edge 20 which is rather sharply concave so that in the assembled and worn garment the edge 20 will curve over and around the instep of the child wearing the garment.

In the finished garment the edges 15 are sewn together to form the outer seam 15' and the edges 18 are sewn together to form the inner seam 18'. Edges 16 are not sewn together but are sewn to corresponding edges of corresponding parts composing the other leg of the garment. A woven elastic waistband 21 is sewn to the top of the garment.

Forming a very material part of this invention is the construction of the boot or foot portions of the garment. Though the boot portion has a moccasin type construction with the roominess of that construction, and though the boot portion has a smooth sole free of any seams or ridges or ribs that might interfere with walking, the boot portion is formed of but two pieces 22 and 23. Piece 22 forms the instep portion and toe cap portion of the boot, while piece 23 forms the sole. The instep-forming piece 22 takes the general form of a blunted and compressed crescent or C. It has a generally semi-elliptical main outer edge 24 and a concave and again generally semi-elliptical inner edge 25. The edges formed by the blunting of the horns of the crescent are composed of a straight edge 26 and a straight edge 27 of about a third the length of the edge 26. The straight edges 26 and 27 are disposed to form a large angle between them, all as best seen in Fig. 4. Formed on the piece 22 is a welt seam taking the general form of a V with its point lying on the symmetrical axis of the piece 22 and with the free ends of the V intersecting the straight edges 26 at about the point where the edges 26 and 27 intersect. Each arm of the V-shaped welt seam in extending away from the point of the V is spaced a progressively increasing distance from the edge 24 for a purpose which will later become more apparent.

The sole-forming piece 23 has a shape generally that of a longitudinal cross section of a tear-drop with the rounded end forming the heel and the pointed end forming the toe of the sole. To give the finished foot portion of the garment a distinctive shoe or boot appearance, as well as to strengthen the garment structurally, a corded tape 30 is sewn to the piece 23 to define the periphery or margin of the sole in the finished garment. For convenience in manufacture, neatness and increased strength, the tape 30, as clearly seen in Figs. 6 and 7, may be sewn to the outer surface of the piece 23 with the corded edge on the inside and spaced inwardly from the edge of the piece 23 by approximately the width of the tape. The margin of the piece 23 carrying the tape 30 is then folded back upon the piece 23 with the tape exposed and facing upwardly, as best seen in Fig. 8. The instep-forming piece 22 has its peripheral edge turned inwardly and the inturned portion 31 placed over the tape 30 and sewn to the sole-forming piece 23.

As best seen in Fig. 1, the edge 25 of the piece 22 is sewn to the concave bottom edge 20 of the front part 12 to form the seam 32, while the edges 26 are sewn to the edges 15 and 18 of the back part 13 to form continuations of the seams 15' and 18'. It will be appreciated that the small edge portions 27 will be taken up in the formation of the seam 32 and that hence the seam

formed by the joining of edges 20 and 25 will intersect the welt seam 28 at the seams 15' and 18'. The securing of the foot portion is completed by sewing the heel of the sole directly to the bottom edge 19 of the back part 13. This, of course, is made possible by the increased length of the lower portion of the part 13 relative to the lower portion of the part 12 with the extension of the part 13 beyond the part 12 serving to form the heel or counter portion of the boot upper.

In the completed garment, the instep-forming piece 22 on the line of the symmetrical axis of the piece extends substantially horizontally from the seam 32 to the toe of the foot. This piece, moreover, measured along its longitudinal center line is, as clearly seen in Fig. 1, shorter than the sole-forming piece measured from its toe end to a point vertically below the point of attachment of said leg and said toe-cap forming piece at the center line thereof. In view thereof, the toe of the foot or boot will turn upwardly to give the boot a resemblance to the upturned toes on the boots or shoes characteristic of jesters in the illustrations in fairy and folk lore tales. To heighten this impression and to provide a source of amusement for the child wearing the garment, each foot may have sewn to the toe thereof a little bell 33.

It is believed apparent from the foregoing that we have perfected a garment which, depending upon the materials from which it is made, can be employed either as a sleeping garment or as a play garment, or both. When employed as a play garment, it dispenses with the necessity for stockings, booties and rompers, and will serve to keep the child warm and protected against cold and drafts associated with the floors of dwellings and also from dirt. Inasmuch as the garment cannot be removed by the child, the feet and legs will not be exposed as is so common when booties are employed because, as above stated, children have such a propensity for removing booties and stockings. Because of the formation of the feet, there is not only ample room but the child may walk comfortably for the bottoms or soles of the foot portions are smooth and free of seams or ribs. Finally, the shaping of the foot portions gives the garment a distinctive and attractive appearance and the addition of the bells will afford a small infant many hours of amusement simply by its kicking, and will afford many hours of entertainment to an older child through examination or by timed ringing either by kicking or by shaking with the hand.

We claim as our invention:

1. A child's trousers-like garment comprising a pair of legs, each leg being composed of a front part and a rear part each forming approximately one-half of the leg, the rear part being somewhat longer than the front part and sewn to the front part to project beyond the bottom edge of the front part, and the front part having a concave bottom edge to overlie and curve around the instep of the child when worn, a foot integral with each leg, each foot comprising a sole-forming piece generally shaped as the longitudinal cross section of a drop and a single instep and toe-cap-forming piece, said last named piece having the shape of a blunted crescent with a rather sharply concave inner edge, a generally V-shaped welt seam formed on said last named piece having its point on the center line of said blunted crescent and having its arms extending from the point toward the blunted points of the crescent to lie

increasingly greater distances inwardly of the outer edge of said crescent shaped piece, said blunted crescent shaped piece being sewn to the leg with the inner edge sewn to the bottom edge of the front part and the blunted points being sewn to the extending portion of the back part at the side edges thereof, said sole being sewn with its rounded portion to the bottom edge of the rear part and with the balance thereof sewn to the outer edge of said blunted crescent shaped piece with the sole spaced from said welt seam decreasing amounts to terminate with the toe of the sole at the tip of the V-welt seam, said toe-cap-forming piece measured along its longitudinal center line being shorter than said sole-forming piece measured from its pointed end to a point vertically below the point of attachment of said toe-cap-forming piece, at its longitudinal center line, to said leg giving the foot a turned up appearance.

2. A child's footed trousers-like garment comprising a pair of legs, each leg being composed of a front part and a rear part forming approximately one-half of the leg, and a foot integral with each leg, each foot comprising a sole-forming portion generally shaped as the longitudinal cross section of a drop and an instep and toe-cap-forming portion having a generally semi-elliptical margin sewn to said sole-forming portion and an inner edge sewn to the front part of said leg, said instep and toe-cap-forming portion measured along its longitudinal center line from its toe end to the point of attachment to the leg being shorter than said sole-forming portion measured from its toe end to a point vertically below the center line point of attachment of said toe-cap-forming portion to said leg to result in an upturned toe.

3. A child's footed trousers-like garment comprising a pair of legs and a foot integral with each leg, each foot comprising a sole-forming portion generally shaped as the longitudinal cross section of a drop and tapering toward a point at the toe end and means forming the foot uppers including an instep and toe-cap-forming portion having a generally semi-elliptical margin sewn to said sole forming portion and an inner, foot-arch-bridging edge sewn to the bottom edge of the front of said leg, said instep and toe-cap-forming portion measured along its longitudinal center line from its toe end to the point of attachment with said leg being shorter than said sole-forming portion

measured from its toe end to a point vertically below the center line point of attachment of said toe-cap-forming portion with said leg to result in a pointed upturned toe.

5 4. A child's trousers-like garment comprising a pair of legs, each leg at the bottom over the front approximate half of the leg being cut away to terminate short of the bottom edge of the rear half of the leg, and a foot integral with each leg, each foot comprising a sole-forming piece generally shaped as the longitudinal cross section of a drop and a single instep and toe-cap-forming piece, said last named piece having the shape in plan of a blunted crescent with a concave inner edge, the outer edge of said last named piece being sewn to the pointed end of said sole-forming piece, the concave inner edge to the bottom edge of the front of said leg, the blunted points to the side edges of the extending portion of the rear half of the leg, and the rounded portion of said sole to the bottom edge of the extending rear half of the leg, said toe-cap-forming piece measured along its longitudinal center line being shorter than said sole-forming piece measured from its pointed end to a point vertically below the point of attachment of said toe-cap-forming piece at its longitudinal center line to said leg, thereby giving the sole of the foot a turned-up appearance at the toe.
